[57] CLAIM

The ornamental design for a massaging head and face mask, as shown and described.

DESCRIPTION

FIG. 1 is a right front perspective of a massaging head and face mask, showing my new design, the facial outline in broken line being shown for illustrative purposes and forming no part of the claimed design;

FIG. 2 is a top plan view, thereof;

FIG. 3 is a front elevational view, thereof;

FIG. 4 is an elevational view of one side;

FIG. 5 is an elevational view of the other side;

FIG. 6 is a rear elevational view thereof; and,

FIG. 7 is a bottom plan view thereof.
